US00D906970S

(12) **United States Design Patent** (10) **Patent No.:** **US D906,970 S**
(45) **Date of Patent:** **** Jan. 5, 2021**

(54) **CONNECTOR**

(71) Applicant: **MASIMO CORPORATION**, Irvine, CA (US)

(72) Inventors: **Kevin Forrest**, Rancho Santa Margarita, CA (US); **Ammar Al-Ali**, San Juan Capistrano, CA (US); **Yassir Kamel Abdul-Hafiz**, Irvine, CA (US)

(73) Assignee: **Masimo Corporation**, Irvine, CA (US)

(**) Term: **15 Years**

(21) Appl. No.: **29/614,043**

(22) Filed: **Aug. 15, 2017**

(51) **LOC (13) Cl.** **13-03**

(52) **U.S. Cl.**

USPC **D13/133; D14/385**

(58) **Field of Classification Search**

USPC D13/107, 110, 118, 120, 123, 133, 146, D13/147, 154, 173, 184, 199; D14/432, D14/433, 385; D24/127, 129, 186

(57) **CLAIM**

The ornamental design for a connector, as shown and described.

DESCRIPTION

FIG. 1 is a top and side perspective view of a connector; FIG. 2 is a top view thereof; FIG. 3 is a bottom view thereof; FIG. 4 is a first side view thereof; FIG. 5 is a second side view thereof; FIG. 6 is a front view thereof; FIG. 7 is a back view thereof; FIG. 8 is a front, top, and side perspective view thereof; FIG. 9 is a front, bottom, and side perspective view thereof; FIG. 10 is a top and side perspective view of a connector; FIG. 11 is a top view thereof; FIG. 12 is a bottom view thereof; FIG. 13 is a first side view thereof; FIG. 14 is a second side view thereof; FIG. 15 is a front view thereof; FIG. 16 is a back view thereof; FIG. 17 is a front, top, and side perspective view thereof; and, FIG. 18 is a front, bottom, and side perspective view thereof. Broken lines are used to illustrate portions of the connector or environmental subject matter that form no part of the claimed design.

1 Claim, 18 Drawing Sheets
